[57] CLAIM

The ornamental design for a baby's thermometer, as shown and described.

DESCRIPTION

FIG. 1 is a front view of a first embodiment of a baby's thermometer in accordance with the invention;

FIG. 2 is an elevational view of the right side of the first embodiment. The left side elevational view of the first embodiment is a mirror image of FIG. 2;

FIG. 3 is a bottom plan view of the first embodiment;

FIG. 4 is a top plan view of the first embodiment;

FIG. 5 is a rear view of the first embodiment;

FIG. 6 is a front view of a second embodiment of a baby's thermometer in accordance with the invention;

FIG. 7 is an elevational view of the right side of the second embodiment. The left side elevational view of the second embodiment is a mirror image of FIG. 7;

FIG. 8 is a bottom plan view of the second embodiment;

FIG. 9 is a top plan view of the second embodiment;

FIG. 10 is a rear view of the second embodiment;

FIG. 11 is a bottom plan view of a third embodiment. The front view is the same as shown in FIG. 6. The side view is the same as shown in FIG. 7.

The rear view is the same as shown in FIG. 10; and,

FIG. 12 is a top plan view of the third embodiment.
